UNITED STATES PATENT OFFICE.

WILLIAM A. SPRING, OF BROOKLYN, NEW YORK, ASSIGNOR TO BIGELOW CARPET COMPANY, A CORPORATION OF MASSACHUSETTS.

DESIGN FOR A RUG.

40,543.

Specification for Design.

Patented Feb. 22, 1910.

Application filed December 16, 1909. Serial No. 533,479. Term of patent 7 years.

To all whom it may concern:

Be it known that I, WILLIAM A. SPRING, a citizen of the United States, residing at Brooklyn, Kings county, State of New York, have invented a new, original, and ornamental Design for Rugs, of which the following is a specification, reference being had to the accompanying drawing, forming a part thereof.

The figure is a plan view of one of the like quarters of a rug, showing my new design.

I claim:

The ornamental design for a rug, as shown.

WILLIAM A. SPRING.
